FIG. 4

Inventor
Enoch J. Larson
By his Attorney
Alfred Schinstiel

UNITED STATES PATENT OFFICE.

ENOCH J. LARSON, OF TRENTON, NEW JERSEY.

JAR-COVER REMOVER.

1,358,452.

Specification of Letters Patent.

Patented Nov. 9, 1920.

Application filed October 24, 1919. Serial No. 332,969.

To all whom it may concern:

Be it known that I, ENOCH J. LARSON, a citizen of the United States, residing at Trenton, county of Mercer, and State of New Jersey, have invented certain new and useful Improvements in Jar-Cover Removers, of which the following is a specification.

This invention relates to improvements in kitchen utilities, and has as its object the provision of a tool which may be used universally for a number of purposes, such as often arise in a dwelling, among which may be enumerated the opening of canned goods, both cylindrical and flat, such as sardines, the removal of screw jar covers, adjusting screws, and in the sharpening of knives, scissors, ice skates, and like edged instruments, all of which are accomplished in a convenient and practical manner.

The principal object of the invention however, resides in the provision of a tool for removing the screw-covers of the ordinary cylindrical cans, of varying sizes, in such manner that the cover of the can may be completely removed, the same being turned from the body in an easy and expeditious manner.

These and other like objects, which will become more fully apparent as the description progresses, are attained by the novel construction and combination of parts hereinafter described, and shown in the accompanying drawings forming a material part of this disclosure, and in which—

Figure 1 is a side elevational view showing an implement in accordance with the invention,

Fig. 2 is a bottom plan view of the same,
Fig. 3 is a top plan view thereof, and

Fig. 4 is a transverse sectional view taken on line 4—4 of Fig. 3.

Referring to the drawings, the numeral 10 indicates a pair of bars disposed in parallel, and connected at one end integrally with a curved element 11, from which extends an offset projection 12, terminating in a round spur 13, having a relatively sharp point 14.

Formed through the main portion of the spur 13 is an elongated slot 15, adapted to receive the free end or tab of flat can covers such as are used for holding sardines and the like, and after the tab has been entered in the slot 15, the implement is rotated in the manner of a key, causing the cover to be severed along the weakened lines as is

usual, so as to be removed from the top of the can. Thus the implement takes the place of the ordinary key used for such purposes, and which, due to its weakness frequently fails in attaining its purpose.

The bars 10 are also joined at their opposite ends with a head 16, the same being extended laterally in both directions, and provided upon its sides with projections 17, which may be used in driving tacks, pins and the like in an obvious manner.

Also extending directly in line with one of the bars 10, is a flat projection 18 terminating in a beveled point 19, adapted to enter the head of ordinary screws whereby they may be turned in or out as desired, the bars in this case acting as a handle for the screw-driver.

Adjacent to the plate 18, is a curved shear blade 20, its edge 21 being engageable by force with an ordinary tin can cover, the bars 10 in this case being used as a lever whereby the shearing effect of the edge 21 may be brought to bear, severing the top of tin cans in an obvious manner.

A pair of prongs 22, having inwardly beveled edges 23, extend rearwardly from the head 16, and are adapted to guide a thin blade, as that of a knife or like cutting instrument, so as to make contact with a hard disk 25 engaged within a recess 26 formed in one side of the head, the disk being held in place by a central projection 28, which extends upward from the body through an opening appropriately formed in the center of the disk 25, and has a transverse opening to receive the cottor-pin or like securing means 29. A pair of recesses 30 and 31 in part 22 formed with beveled edges constitute with the disk 25 wire cutters or the like.

Extending down from the sides of the body, opposite the disk, is a pair of angular projections 33, terminating in spur points 34, the points of the projections 33 being at a suitable distance from the main body 16, to cause the same to engage with the usual screw-threaded metallic covers as used in connection with fruit and other like jars so that a sufficient grip is obtained upon the same.

Cooperative with the spur elements 34 are forwardly extending projections 35, formed with a metallic slide 36, the projections being at right angles to the main body of the slide, from which extends another parallel projection 37, terminating in a

sharp point 38, the purpose of which will be hereinafter described.

Formed in the inner side of the bars 10 are longitudinal recesses 40, in which the 5 widened portion of the slide body 36 is adapted to engage; while upon the opposite sides of the bars 10 are formed a plurality of transverse sockets 42, engageable with the angularly turned edges 43 of the slide, 10 so as to be positively held in position.

In operating the device in connection with the screw cover of a jar, the slide is moved toward the spurs 34, until these spurs and the elements 35 contact with the opposite 15 sides of the jar cover, whereupon the implement is rotated by the extending portion, the thumb of the operator resting upon the slide 36 so as to hold it engaged within the slot, and due to the leverage the can cover 20 will be caused to move upon the screw thread.

In operating upon an ordinary cylindrical can, the spur 13 is forced into the top of the can approximately at the center thereof, 25 and the cutter spur 38 pressed downwardly into the can cover adjacent to its margin, whereupon the implement is rotated upon the axis of the element 12, completely severing the center of the cover from the body, 30 permitting it to be removed thereby giving access to the entire contents of the can.

From the foregoing it will be seen that an effective implement of the class described has been disclosed which is convenient and 35 practical for a number of uses, while the adjustable feature relative to cans or covers

is such as to render the implement useful for domestic purposes.

Having thus described my invention and set forth the manner of its construction, application, and uses, what I claim as new and desire to secure by Letters Patent, is—

1. In a device of the class described, the combination with a head, a pair of bars extending therefrom, and a pair of projections extending downwardly from said head, of longitudinal recesses formed in the inner sides of said parallel bars, a slide engageable therewith, and an element formed with said slide coöperative with said pair of projections adapted to engage with the screw cover of a can for removing said cover. 45 50

2. In a device of the character described, the combination with a head, a pair of bars 55 extending therefrom provided with a plurality of transverse sockets on opposite sides, and longitudinal recesses on the other inner sides of the bars, and a pair of projections extending longitudinally from said head, of a slide provided with forwardly extending projections adapted to be coöperated with said head projections to engage a jar cover, and a pair of angularly turned edges on said slide engaging with the sockets of said bars, the widened part of said slide engaging the longitudinal recesses of 60 65 said bars, substantially as described.

In testimony whereof I have affixed my signature.

ENOCH J. LARSON.
